UNITED STATES PATENT OFFICE

PEIRCE M. WOOD, OF NEW ROCHELLE, NEW YORK, ASSIGNOR, BY MESNE ASSIGNMENTS,
TO HOBART MANUFACTURING COMPANY, OF TROY, OHIO, A CORPORATION OF OHIO

CONVEYER MECHANISM FOR WASHING MACHINES

Original application filed October 31, 1925, Serial No. 65,923. Divided and this application filed November 5, 1926. Serial No. 146,530. Renewed June 17, 1930.

This invention relates to conveyer mechanism for washing machines.

The invention aims to provide a connection between racks containing articles to be washed and a conveyer which is sufficiently positive to prevent undesired slippage of the racks but capable of yielding when necessary to prevent breakage of the articles contained in the racks.

10 The means by which this object is attained in accordance with the invention can best be understood by a detailed description of a practical conveyer mechanism embodying the invention, which is shown in the accompanying drawings, in which:

Fig. 1 is a side elevation of the conveyer mechanism indicating diagrammatically the casing of the washing machine in which it is contained; and

20 Fig. 2 is an enlarged fragmentary side view of one of the conveyer chains and a dish rack resting thereon, showing the engagement between the rack and the chain.

The conveyer mechanism is provided for 25 moving the articles to be washed through the casing 10 of a washing machine from an entrance opening 11 at one end of the casing to a discharge opening 12 at its other end.

Any usual washing means may be provided to 30 act upon the articles as they are carried through the casing. The conveyer mechanism includes, in addition to a number of racks 15 in which dishes or other articles may be placed, chains 20 extending the length of the 35 washing machine casing. The chains 20 run over pairs of sprockets 22, 23 mounted on shafts 24, 25 located within the washing machine casing and extending across it near its ends. The shaft 24 is driven from any convenient source of power.

To prevent the dish racks 15 from slipping on the conveyer chains, they are provided on their bottoms with projections 16 formed by bends in metal bands 17 which are secured to 45 each dish rack so as to extend along its bottom at the side edges thereof. The projections 16 have curved and inclined sides and fit between the rungs 26 of the chains and in curved recesses 27 on the upper side of the 50 links of the chains. The inclined engaging

surfaces of the rack projections and the chains have an important function in preventing breakage of the dishes or of the machine when a dish rack becomes accidentally wedged against movement in the machine, or when dish racks are held at the discharge end of the machine so as to prevent those in the machine from moving. In either case, the chains do not force the dish racks forward, but merely raise the inclined projections 16 and 55 the dish racks sufficiently to pass under the projections.

This application is a division of my co-pending application, filed October 31, 1925, Serial No. 65,923.

What is claimed is:

1. In a dish washing machine, the combination of a conveyer and an article-carrier resting thereon, the opposed surfaces of the carrier and conveyer being provided with co-operating projections and recesses having rearwardly and upwardly inclined engaging surfaces, so that the conveyer raises the carrier when the carrier is held against forward movement.

2. In a dish-washing machine, the combination of a conveyer chain, a rack resting on the chain and having a short tapering projection extending between the rungs of the chain.

3. In a washing machine, the combination of a conveyer chain having links each provided with a curved recess in its upper edge, and a rack resting on the chain and having a projection extending into the curved recess in a link of the chain.

In testimony whereof I have hereunto set my hand.

PEIRCE M. WOOD.
